FENCE POST

Dale A. Neidhardt, New Salem, N. Dak. 58563

Filed Jan. 26, 1968, Ser. No. 10,324

Term of patent 14 years

U.S. Cl. D28—1
Int. Cl. D25—01

FIG. 1 is a top plan view of a fence post showing my new design;

FIG. 2 is a fragmentary perspective view thereof;

FIG. 3 is a front elevation thereof;

FIG. 4 is a side elevation thereof;

FIG. 5 is a side elevation of the side opposite that shown in FIG. 4; and

FIG. 6 is a perspective view thereof as seen from the open face of the fence post.

I claim:

The ornamental design for a fence post, as shown and described.
